ELECTROMAGNETIC DEVICE

Donald A. Lace, Chicago, Ill., assignor of one-fifth to
Nicholas M. Esser, Melrose Park, Ill.

Application June 10, 1955, Serial No. 514,433

16 Claims. (Cl. 200—87)

This invention relates to electromagnetics and more particularly to an electromagnetic device having improved operating characteristics.

It is the principal object of this invention to provide an electromagnetic device having optimum operating characteristics for minimum coil size and current consumption.

An outstanding feature of the present invention resides in its adaptability to extremely minute dimensions.

These objects and additional features and advantages will become more readily apparent as the following description proceeds taken in conjunction with the following drawings wherein:

Fig. 1 is a side elevation of an electromagnetic device in accordance with this invention illustrated in connection with a striker for a bell, gong or other audible device.

Fig. 2 is an exploded view of the components of the device illustrated in Fig. 1.

Fig. 3 is a top view of Fig. 1 with the armature removed for clarity.

Fig. 4 is a side elevation schematically illustrating an electromagnetic device in accordance with this invention in the form of a relay.

Fig. 5 illustrates an exploded view of components for a modified form of electromagnetic device such as that of Fig. 1.

Fig. 6 is a top assembled view of the device of Fig. 5.

Referring now more particularly to Figs. 1 to 3 of the drawings, numeral 10 represents a magnetic yoke structure having a base 11, an upstanding web 12 extending from one end of the base 11 and an upper inturned member 13 which lies preferably in a plane parallel to the base 11 but of considerably shorter length. The base 11 is provided with a central bore 14, into which a reduced end 16 of the magnetic pole 17 is fitted. A pole structure is provided by preferably presecuring the pole 17 to an extension thereof 18 which preferably lies in the same plane as that of member 13 and which forms with the yoke 10 and the pole 17 the entire electromagnetic circuit or structure. The reduced end 16 of the pole 17 may be provided with an internally threaded bore into which a screw 19 may be threaded, thereby securing the structure to the base 11 of the yoke, or it may be merely upset and peened over to so secure it.

A coil 20, in the form of a solenoid, may be placed to snugly circumscribe the pole 17 before it is secured to the yoke 10 or the coil may be pre-wound directly upon the pole 17 of the pole structure 16, 17, 18.

Referring particularly to Fig. 3, it will be noted that the member 18 is shaped complementary to the coil 20 except for its rear edge 21, which is straight. The edge 21 is closely spaced from the edge 22 of the inturned member 13 of the yoke structure 10 in such a manner as to form a small air gap of the order of a few thousandths of an inch, and in the preferred embodiment illustrated, .018". To the upstanding web 12 of the yoke there is secured by any suitable means, such as for example, screws 23, a non-magnetic, armature supporting structure

2

24. This may conveniently be formed of brass and precision shaped into a C-shaped structure having only three walls. The upper edges 25 of the lateral sides of this structure may be sloped at a small angle with respect to the plane of the top surfaces 13 and 18 of the magnetic structure, this angle being of the order of 1° to 5° and preferably 1°. The connection of the non-magnetic member to the web 12 is such that the lower armature surface is always substantially tangential to the upper portion of a radius or curved pivot 26, formed in the bending over of the upper magnetic portion 13 from the upstanding web 12.

However, the upper edges 25 may be flat and lie in a plane parallel to the plane of members 13 and 18. The position of the edges 25 with respect to member 13 may be adjusted by means of the slot-like apertures 29 in the cross wall of the supporting structure 24. The range of adjustability is such that the armature position, to be described presently, is maintained at rest with respect to surfaces 13 and 18 at an angle of 1° to 5°.

It is to be understood that the armature supporting structure 24 may comprise any non-magnetic material and need not be metal. It may comprise, for example, a resin or rigid plastic insulating material. The shape may also vary and may be solid so long as the slope characteristics imparted thereby to the armature remain in the range specified.

Two aligned positioning pins 27 are provided near opposite sides of the structure 24. The lateral walls of the structure 24 may also be provided with one or more pairs of aligned bearing holes 28, the purpose for which will appear shortly.

The magnetic device is completed with an armature 30 of magnetic material and is substantially rectangular but may have a rounded end to match that of the base 11. It is provided toward its rear edge 31 with a pair of notches or bores 32, which fit about the guide pins 27. It is further provided with an intermediate aperture 33. The armature 30, guided by pins 27, is connected to the non-magnetic supporting structure 24 or the yoke 10 by means of a pin 35 extending through the aperture 33 and anchored at any convenient place and by any convenient means, for example on the cross wall of the structure 24 by means of a threaded or hook and eye connection.

The armature 30 is held in place under the moderate tension of a coil spring 36 between the armature and the head of the pin 35 which it surrounds. In the embodiment illustrated, the spring 36 is positioned above the armature but obviously can be positioned beneath as well. The position of the spring may be varied but it is preferable that it be positioned closer to the radiused pivot than to the rear pivot position of the armature. The rear lateral sides of the armature 30 in the rest position, therefore, are supported on the top edges 25 of the armature supporting structure 24 so that the armature bears tangentially upon the upper portion of the radiused surface 26 of the magnetic piece 13 at a small angle to the top surfaces 13 and 18 of the magnetic circuit and closely adjacent the air gap. It will be apparent, therefore, that when the coil 20 is energized, the armature will be rocked downwardly about the radiused pivot 26, immediately closing the air gap between edges 21 and 22, and storing up mechanical energy in the spring 36. When the circuit to the coil 20 is opened, the armature will move toward its rest position under the stored up energy of the spring 36 and will rock at least one or more times about its rearmost pivot edge 31 until it comes to a rest position.

If necessary, a thin non-magnetic buffer material, such as aluminum foil may be placed between the armature and surface 18 to control possible sticking due to residual magnetism. Obviously, a simple self-interrupting circuit can be arranged and timed to utilize whatever number of

oscillations, preferably one, in this return rocking arrangement, as is desired.

In the embodiment shown, a striker or clapper member 40 is attached by arms 41 to a pivot shaft 42, secured through aligned bores 28 in the lateral walls of the non-magnetic member 24. A simple self-interrupted circuit for the coil 20 may be arranged through mating contacts 43 on the clapper and an isolated contact 37 on the armature. Such a circuit is schematically illustrated in Fig. 1. Depending on the operating position of such a device, a spring 44 to bias the clapper toward contact position may be required.

The magnetic structure of this device is so efficient that considerable energies can be transferred to the clapper member 40 of such a magnetic device employing an extremely minute coil. The entire coil, whether pre-wound on pole 17 or wound as a solenoid and placed thereover, need not exceed in outside diameter the diameter of a standard pencil eraser, and is preferably wound of copper wire ranging about .42 to .43 wire size, and having a total resistance of 20 to 40 ohms, and preferably 30 ohms. The length of the arms 41 need not exceed $\frac{5}{16}$ inch and this entire magnetic device, operating self-interrupted, will drive a one ounce clapper 10 to 12 oscillations per second at a current consumption of less than one milliampere per hour. In other words, powered by a single standard penlight dry cell, a magnetic device of this type will operate continuously for 300 hours or more. The current consumed in watts, therefore, is of the order of $\frac{1}{20}$ to $\frac{1}{40}$ of a watt. It will be apparent that the compactness and efficiency of its magnetic circuit lends this device particularly well to any need for a magnetic structure, either self-interrupted or energized and released at will, especially where extremely small dimensions and currents are required. The entire device with clapper need not exceed the dimensions of a one-half inch cube.

In Fig. 4 the same magnetic structure with pairs of contacts 45 and 46 illustrates schematically extremely efficient relay arrangements of minute size. In Fig. 4, the insulating properties of a non-metallic—non-magnetic armature supporting structure 24 may be utilized to mount a pair of relay contacts such as 46, operated by the rear of the armature 30 by an arm 47.

Figs. 5 and 6 illustrate a modified form of the magnetic structure resulting in even greater efficiencies, like numbers being assigned to like members.

Certain modifications and changes will be suggested hereby to those skilled in the art, and it is intended that all such revisions and modifications as fall within the true spirit of this invention are included within its scope as best defined by the appended claims.

I claim:

1. An electromagnetic device comprising a yoke structure of magnetic material having a base and an upstanding web connected to one end of the base, a pole fixed to the base, a coil disposed about said pole, an extension of said pole adjacent said yoke structure, and spaced therefrom by a narrow air gap, an armature supporting member of non-magnetic material secured to the yoke structure, and an armature, biasing means urging said armature toward simultaneous engagement with the ends of the web distal from the base and a portion at least of said armature supporting member, said armature extending at rest over said extension of said pole, adapted to rock about the yoke structure when the coil is energized and about a pivot on the supporting member on deenergization of the coil.

2. An electromagnetic device comprising a yoke structure of magnetic material having a base and an upstanding web connected to one end of the base, a pole fixed to the base, a coil disposed about said pole, an extension of said pole adjacent said yoke structure, and spaced therefrom by a narrow air gap, an armature supporting member of non-magnetic material secured to the yoke structure, and an armature, biasing means urging said armature toward simultaneous engagement with the ends of the

web distal from the base and a portion at least of said armature supporting member, said armature extending at rest over said extension of said pole, and at a slight angle thereto, adapted to rock about the yoke structure when the coil is energized and about a pivot on the supporting member on deenergization of the coil.

3. An electromagnetic device comprising a yoke structure of magnetic material having a base and an upstanding web connected to one end of the base, a pole fixed to the base, a coil disposed about said pole, an extension of said pole adjacent said yoke structure and spaced therefrom by a narrow air gap, an armature supporting member of non-magnetic material secured to the yoke structure, and an armature, biasing means urging said armature toward simultaneous engagement with the ends of the web distal from the base and a portion at least of said armature supporting member, said armature extending at rest over said extension of said pole, adapted to rock about the yoke structure when the coil is energized and about a pivot on the supporting member on deenergization of the coil, the end of the web distal from said base being provided with a radius whereby a continuous and progressive magnetic contact is maintained with the armature as it rocks thereabout.

4. An electromagnetic device as claimed in claim 1, in which said armature supporting member comprises an insulating material.

5. An electromagnetic device comprising a yoke structure of magnetic material having a base and an upstanding web connected to one end of the base, a pole fixed to the base, a coil disposed about said pole, an extension of said pole adjacent said yoke structure and spaced therefrom by a narrow air gap, an armature supporting member of non-magnetic material secured to the yoke structure, and an armature, biasing means urging said armature toward simultaneous engagement with the ends of the web distal from the base and a portion at least of said armature supporting member, said armature extending at rest over said extension of said pole and at a slight angle thereto, adapted to rock about the yoke structure when the coil is energized and about a pivot on the supporting member on deenergization of the coil, the position of said armature supporting member being adjustable with respect to said yoke to vary the angle of the armature at rest with respect to the upper surface of the extension of the pole.

6. An electromagnetic device comprising a yoke structure of magnetic material having a base and an upstanding web connected to one end of the base, a pole fixed to the base, a coil disposed about said pole, an extension of said pole adjacent said yoke structure and spaced therefrom by a narrow air gap, an armature supporting member of non-magnetic material secured to the yoke structure, and an armature, biasing means urging said armature toward simultaneous engagement with the ends of the web distal from the base and a portion at least of said armature supporting member, said armature extending at rest over said extension of said pole, adapted to rock about the yoke structure when the coil is energized and about a pivot on the supporting member on deenergization of the coil, a swinging member provided with a pair of arms straddling said yoke and coil, said member being pivotally mounted to said armature supporting member and adapted to be struck by said armature to swing it about its pivotal mounting, and self-interrupted circuit means for operating said coil to intermittently swing the swinging member about its said pivotal mounting.

7. An electromagnetic device comprising a yoke structure of magnetic material having a base and an upstanding web connected to one end of the base, a pole fixed to the base, a coil disposed about said pole, an extension of said pole adjacent said yoke structure and spaced therefrom by a narrow air gap, an armature supporting member of non-magnetic material secured to the yoke struc-

ture, and an armature, biasing means urging said armature toward simultaneous engagement with the ends of the web distal from the base and a portion at least of said armature supporting member, said armature extending at rest over said extension of said pole, adapted to rock about the yoke structure when the coil is energized and about a pivot on the supporting member on deenergization of the coil, and at least one pair of relay contacts operable by said armature.

8. An electromagnetic device comprising a yoke structure of magnetic material having a base and an upstanding web connected to one end of the base, a pole fixed to the base, a coil disposed about said pole, an extension of said pole adjacent said yoke structure and spaced therefrom by a narrow air gap, an armature supporting member of non-magnetic material secured to the yoke structure, and an armature, biasing means urging said armature toward simultaneous engagement with the ends of the web distal from the base and a portion at least of said armature supporting member, said armature extending at rest over said extension of said pole, adapted to rock about the yoke structure when the coil is energized and about a pivot on the supporting member on deenergization of the coil, said armature supporting member comprising an insulating material, and at least one pair of relay contacts secured to said armature supporting member of insulating material and operable by said armature.

9. An electromagnetic device comprising a yoke structure of magnetic material having a base and an upstanding web connected to one end of the base, a pole fixed to the base, a coil disposed about said pole, an extension of said pole adjacent said yoke structure and spaced therefrom by a narrow air gap, an armature supporting member of non-magnetic material secured to the yoke structure, and an armature, biasing means urging said armature toward simultaneous engagement with the ends of the web distal from the base and a portion at least of said armature supporting member, said armature extending at rest over said extension of said pole and at a slight angle thereto, adapted to rock about the yoke structure when the coil is energized and about a pivot on the supporting member on deenergization of the coil, at least one surface of the armature supporting member and upon which the armature bears when the coil is deenergized being provided with a slope substantially equal to the angle at which the armature extends with respect to the extension of said pole.

10. An electromagnetic device comprising a yoke structure of magnetic material having a base and an upstanding web connected to one end of the base, a pole fixed to the base, a coil disposed about said pole, an extension of said pole adjacent said yoke structure and spaced therefrom by a narrow air gap, an armature supporting member of non-magnetic material secured to the yoke structure, and an armature, biasing means urging said armature toward simultaneous engagement with the ends of the web distal from the base and a portion at least of said armature supporting member, said armature extending at rest over said extension of said pole, adapted to rock about the yoke structure when the coil is energized and about a pivot on the supporting member on deenergization of the coil, the means biasing the armature toward said armature supporting member being positioned closer to the web than to the position where the armature pivots on the armature supporting member.

11. An electromagnetic device comprising a yoke structure of magnetic material having a base and an upstanding web connected to one end of the base, an inturned

5

projection extending from the other end of said web in the same direction as the base, a pole fixed to the base and having a portion extending to adjacent said inturned projection and spaced therefrom by a narrow airgap, a coil disposed about said pole between the portion extending therefrom and the base, an armature supporting member of non-magnetic material secured to the yoke structure, and an armature, biasing means urging said armature toward simultaneous engagement with portions at least of the inturned projection and the armature supporting member, said armature extending at rest over said portion extending from said pole at a slight angle thereto and adapted to rock about the juncture of the inturned projection and the web when the coil is energized and about a pivot on the supporting member on deenergization of the coil.

10 12. An electromagnetic device as claimed in claim 11, in which the juncture of the web and the inturned projection is radiused whereby a continuous and progressive 15 magnetic contact is maintained with the armature as it rocks thereabout.

12 13. An electromagnetic device as claimed in claim 12, in which the means biasing the armature is positioned closer to said radiused pivot than to the position where 20 the armature pivots on the armature supporting member.

13 14. An electromagnetic device as claimed in claim 12, including a swinging member pivotally mounted to said 25 armature supporting member and adapted to be struck by said armature to swing it about its pivotal mounting, and self-interrupted circuit means for operating said coil 30 to intermittently swing the swinging member about its said pivotal mounting.

14 15. An electromagnetic device as claimed in claim 12, including at least one pair of relay contacts operably by 35 said armature.

15 16. An electromagnetic device comprising a yoke structure of magnetic material having a base and at least one upstanding extension connected to the end of the base, a pole connected to the base adjacent said upstanding extension, a coil disposed about said pole, an extension of 40 said pole positioned adjacent said yoke structure and spaced therefrom by a narrow air gap, an armature supporting member of non-magnetic material secured to the yoke structure, an armature, said armature being supported by said non-magnetic material and said yoke structure, the said armature extending at rest over the extension of said pole and adapted to rock about said non-magnetic material and said yoke structure upon energization and deenergization of the coil, and biasing means 45 normally urging said armature simultaneously against the said yoke structure and the supporting member of non-magnetic material secured to the yoke structure.
